UNITED STATES PATENT OFFICE.

WILLIAM E. WOODARD, OF FOREST HILLS, NEW YORK.

LOCOMOTIVE.

Application filed December 26, 1922. Serial No. 608,896.

To all whom it may concern:

Be it known that I, WILLIAM E. WOODARD, a citizen of the United States, residing at Forest Hills, in the county of Queens and 5 State of New York, have invented certain new and useful Improvements in Locomotives, of which the following is a specification.

This invention relates to locomotives and 10 its nature, objects and advantages will be best understood from the following brief description of certain of the difficulties encountered in present practice.

In locomotive design, the factor of adhesion of the drivers for the respective classes of locomotives to meet the requirements of the service for which the locomotive is intended, is so well defined and established and varies within such narrow limits that there 20 may be said to be a standard or normal factor of adhesion for the various locomotives. If the factor of adhesion were low, there would be excessive wheel slippage making it even impossible, in some cases, to start a 25 train, let alone keeping it in motion at slow speeds without stalling; while if it were high, among other things, the operation would not be economical in consumption of steam, which latter can be obtained best with 30 a low factor of adhesion.

Hence, the normal factor of adhesion of existing practice represents a compromise, and, therefore, really meets neither condition satisfactorily; for in starting and at slow 35 speeds there is still objectionable slippage at the peaks of the torque curve and economy in steam consumption is not what it should be.

It is one of the primary objects of my invention to provide a locomotive which meets these conditions satisfactorily and which shall have the possibilities of the steam economy incident to a low factor of adhesion (lower than the normal factor) and yet have 40 the ability to start a train and sustain motion at slow speeds without stalling incident to a high factor of adhesion (higher than the normal factor).

I accomplish the foregoing, together with 50 such other objects as may hereinafter appear, or are incident to my invention by means of a construction, the preferred form of which I have illustrated in the accompanying drawings, of which:

Fig. 1 is a diagrammatic side elevation of

a locomotive embodying my invention; and Fig. 2 is a torque curve illustrating the operation and certain of the advantages thereof.

Referring now to Fig. 1, the locomotive, in general, is of a construction now in use but the factor of adhesion of the main drivers 7 is well below the normal factor of adhesion of a locomotive of this class, the locomotive shown being of the 2-8-2 or Mikado type having a normal factor of adhesion of approximately 4. The elements determining the factor of adhesion are the weight upon drivers, the diameter of the drivers, the diameter and stroke of the pistons, and the operating pressure. For a given type of locomotive or class of service, the weight on drivers, the diameter of the drivers, and the stroke of the pistons are well established, and while it might be possible to alter the factor of adhesion by varying one of these elements, this does not present the same possibilities in economy that a variation in the operating pressure or diameter of the pistons does. I, therefore, propose to decrease the factor of adhesion of the main drivers either by an increase in operating pressure or an increase in piston diameter, preferably the latter. The cylinders 8 are thus of larger diameter than standard and the locomotive may be said to be "over-cylndered."

By using large cylinders, it follows that at the higher speeds the engine may be worked, at shorter cut offs than customary for a given draw bar horsepower; and the shorter the cut off, the greater the economy in steam consumption for the reason that the steam is used more expansively in the cylinders than is possible with a locomotive having cylinders of standard size. Thus, in hauling the same load, a locomotive built in accordance with my invention will operate at shorter cut offs and with the resultant improved steam economy compared with a locomotive of standard construction, or, stated otherwise, a greater load may be hauled with substantially the same steam consumption.

With such low factor of adhesion, however, there would be excessive wheel slippage and consequent loss of power and possibility of stalling. This slippage occurs at the peaks of the torque curve which is an irregular curve with marked high points even in locomotives of standard design.

Such a curve is illustrated in Fig. 2 at A. When this occurs in a standard locomotive, the driver eases off or reduces the steam pressure relying on the momentum of the train to move the engine to a new point where a fresh grip may be had on the rail or to a lower portion of the torque curve, but this frequently results in stalling because of the reduction in draw bar pull.

10 The reason this is done is because the coefficient of friction is much less when the wheels slip with respect to the rail. I propose to carry the locomotive over the torque peaks should the main drivers start to slip by means of an auxiliary motor and driving mechanism which moves the locomotive until a fresh grip may be had by the main drivers. This auxiliary driving mechanism has a factor of adhesion preferably considerably higher than the normal factor and, in the embodiment shown, the auxiliary motor 9 is carried on the trailer truck and drives the wheels 10 thereof, such wheels generally being of small diameter.

15 25 The torque curve of this driving mechanism is illustrated at B in Fig. 2 and it will be observed that it is much flatter than the curve A and that the peaks are also much closer together and bear no relation to the peaks of the curve A, i. e., they are not in synchronism.

20 25 The operation of the auxiliary motor in starting and at slow speeds, therefore, reduces slippage of the main drivers because it sustains motion and thus tends to maintain a grip of the main drivers on the rail: The sustained motion immediately checks incipient slippage.

25 30 By the construction described, I have made it possible to successfully operate a locomotive with a factor of adhesion normally prohibitive and thereby secured the benefits in steam economy resultant from the use of larger cylinders, while at the same

time the locomotive can start the train and sustain motion.

Steam is supplied to the auxiliary motor by the pipe 12 connected to the main steam supply line at 13, the pipe 12 being controlled by a throttle 14.

50

What I claim is:

1. The combination of a locomotive having an appreciably greater proportion of tractive power to weight on drivers than normal for the particular class of locomotives, and an auxiliary motor and driving mechanism for carrying the locomotive over the torque peaks at which slippage of the engine drivers would occur.

2. The hereinbefore described process of operating a locomotive having an appreciably greater proportion of tractive power to weight on drivers than normal for the particular class of locomotives which consists in aiding the main drivers over the torque peaks in starting and slow speeds and thereafter operating the locomotive at relatively short cut offs as compared to standard practice for the particular type and class of service.

3. The herein described process of operating a locomotive having appreciably over-powered cylinders for the particular class of locomotives which consists in aiding the main drivers over the torque peaks in starting and at slow speeds by an auxiliary motor mechanism and wheels, the factor of adhesion of which is relatively high.

4. The combination with a locomotive appreciably over-cylindered for the particular class, of an auxiliary motor and driving mechanism carrying the locomotive over the torque peaks at which slippage of the engine drivers would occur.

In testimony whereof, I have hereunto signed my name,

WILLIAM E. WOODARD.
